SHEET FOLDING

John William Cordell, Oklahoma City, Okla.

Application April 24, 1944, Serial No. 532,510

3 Claims. (Cl. 229—92.1)

This invention relates to sheet folding, and more particularly to the folding of a single sheet of paper to form a combination envelope and sealed voting ballot enclosed by the envelope.

The present absentee voting law in many States requires that the absent voter be furnished with a blank voting ballot; an envelope for returning the ballot under seal; a blank affidavit of voting qualification; a blank power of attorney authorizing some person in the home precinct to cast the ballot; a sheet of instructions; and a copy of the absentee voting law. In addition to the above listed papers, the proper election board must also send the absent voter an envelope for returning the papers, and when the outside envelope in which the papers are mailed is included in the total, it is found that the total is made up of three envelopes and five papers which must be transmitted to the absent voter. Of these, the voter must return the ballot sealed in an envelope; the power of attorney; the affidavit; and the envelope of transmittal, or a total of two envelopes and three papers.

The above totals are formulated upon the presumption that only one ballot is to be voted by the absent voter. Obviously, there would usually be two or more of such ballots to be cast, and the total papers would be thereby increased.

The Secretary of War and the Secretary of the Navy have requested that all States limit the maximum weight of such papers as may be transmitted through the mails to enable a single absentee voter to cast his ballot to eight-tenths of one ounce. In order to come within this weight limit, the above listed papers must be printed upon very thin and light paper. It is also pointed out that the necessary papers, now used to enable an absentee to cast his ballot, must be printed separately. These requests and the principle underlying them have been approved by the 78th Congress (2nd Session) as follows:

"(e) It is further recommended that the several States, in order to reduce the weight and bulk of air transport of absentee voting material being sent to persons to whom this act is applicable, reduce in size and weight of paper, as much as possible, envelopes, ballots, and instructions for voting procedure."

It is the prime object of the present invention to so design a single sheet of paper, that it may be printed front and back, with one printing operation for each, and when properly folded and sealed, will fulfill all of the offices now being carried out by the various papers above men-

tioned, except the outside envelope in which the papers are originally sent to the absentee voter.

In so doing the printing cost is reduced, paper is saved, and the maximum paper weight under the postage regulations allowed by the law, is complied with, without reducing the thickness of the paper to an extent falling below practicability.

Another result intended to be accomplished by the present invention, is the elimination of a chance that the absentee voter may inadvertently fail to return all of the required papers. Should this occur, it would not likely be discovered until the voting day which would be too late to correct the error, and would result in loss of his voting privilege.

One principal object of the invention is to provide a combination sheet and envelope in which a return address may be printed upon an inside portion thereof, and in which that portion may be later partially severed from the portion, bent over another portion of the envelope and stuck thereto to form a return address portion for the envelope.

Other objects will be apparent from the accompanying description when taken in connection with the accompanying drawing wherein:

Figure 1 is a perspective view showing the inside face of the article as it appears when opened; and,

Figure 2 is a similar view of the outside surface of the article.

Like characters of reference designate like parts in both the figures.

In the drawing:

The reference numeral 1 indicates as a whole a flat blank, preferably paper, cut to form a central panel 2, a left hand panel 3 integrally joined to the edge of the central panel 2, and a right hand panel 4 integrally joined to the right hand edge of said central panel 2. The upper edge of the central panel 2 is an elongation or extension 5, which forms a sealing tab or flap as will be more fully described hereinbelow. The inside faces of the panels 2 and 3, which are those faces shown in Fig. 1, are adapted to receive a printed ballot. The upper, lower, and left hand edges of the left hand panel 3 may be gummed, or only the left hand edge portions may be gummed as shown at 6 so that when the panel is folded over the central panel 2 by being bent along the line 7, the panel 3 may be sealed flatly against the central panel 2, as indicated by the arrow at the left central portion of Fig. 1. The next fold to be made in preparing the folder for

mailing is to bend the right hand panel 4 along the dotted line 8 in the direction to bring the panel 4 flatly over the previously folded left hand panel 3. The last operation in completing the folder for mailing is to bend the sealing tab or flap 5 downwardly over the upper portion of the outside or rear surfaces of the panels 3 and 4, and seal it in place by moistening the gummed portion 19 of the sealing tab or flap 5. In the folder above described the right hand panel 4 is adapted to bear the voter's qualifying affidavit on one side and a power of attorney on the opposite side or face authorizing some person to cast the vote. When the folder has been sealed as above described it will be seen that the person to whom the missile has been addressed may cut with a pen knife along the line 10, and by so doing he will release the panel 4 so that it may be opened to disclose the affidavit and power of attorney. This opening will not in any way dispose to view the ballot carried by the inside faces of the panels 2 and 3 which will remain sealed due to the gummed portions 6. The person may then tear off the panel 4 and present it to the Election Board as his authority to cast the ballot. This is done by tearing along the milled line 8.

The upper portion of the right hand panel 4 (Fig. 1) is line perforated horizontally as shown by the line 20, and this perforated line 20 forms a small panel 21 adapted to bear the voter's return address upon its inside or front face. The rear face of the small panel 21, which is the face shown in Fig. 2, has its edge portions 22 covered with gummed mucilage. After the folder has been sealed for mailing the panel 21 is torn along the line 20 and the gummed rim 22 is stuck to the outside face of the panel 2 and bears the sender's return address. This portion 21 can then be torn off before the ballot is dropped into the ballot box so that the identification of the sender will not be known to the person counting the vote.

From the above description it is thought to be evident that a voting ballot has been provided wherein the amount of paper has been saved and conserved to the minimum, and which will eliminate several printing operations in that it can be printed front and back in only two operations.

The embodiment is such that various amounts of space can be provided according to the amount of printing required, and it is evident that the principle herein disclosed could possibly be used for printed matter other than the voting ballot, instructions, affidavit, power of attorney, and absentee voting laws, or rules.

Having thus described my invention, what is desired to be secured by Letters Patent is:

I claim:

1. A combination envelope and voting ballot comprising a single sheet body blank, creased, cut and folded to form: a central panel; a second panel formed at one edge of said central panel and adapted to be folded over said central panel; a gummed edge portion carried by the free side edge of said second panel for sealing the same in such folded position against the central panel; a removable third panel formed at the other edge of said central panel and adapted to be folded over said second panel; a scored line at the junction of said central and third panels whereby the third panel may be torn off; a flap at one edge of said central panel adapted to be folded over the three panels; a gummed portion along the free edge of the flap for sealing the panels in their folded positions; a horizontal line of perforations extending across the third panel separating it into two portions, one side of the upper portion being gummed whereby it may be torn along the perforated line, be folded around the edge of the central panel, and be pasted thereto for bearing a return address.

2. A combination envelope and voting ballot comprising a single sheet body blank, creased, cut and folded to form: a central panel; a gummed portion along one edge thereof whereby it may be folded upon itself and sealed in such folded position; a second panel formed at one side edge of the central panel and adapted to be folded over the central panel; and a horizontal line of perforations extending across the second panel separating it into upper and lower portions, one side of the upper portion being gummed whereby it may be torn along the perforated line, be folded around the edge of the central panel, and be pasted thereto for bearing a return postal address.

3. A combination envelope and voting ballot comprising a single sheet body blank, creased, cut and folded to form: a central panel; a gummed portion along one edge thereof whereby it may be folded upon itself and sealed in such folded position; a second panel formed at one side edge of the central panel and adapted to be folded over the central panel; a horizontal line of perforations extending across the second panel separating it into upper and lower portions, one side of the upper portion being gummed whereby it may be torn along the perforated line, be folded around the edge of the central panel, and be pasted thereto for bearing a return postal address; a flap at the upper end edge of the central panel adapted to be folded over the two panels; and a gummed portion along the free edge of said flap for sealing the panels in their folded positions.

JOHN WILLIAM CORDELL.
